US0D1111187S

(12) **United States Design Patent** (10) Patent No.: **US D1,111,187 S**
(45) Date of Patent: ** Feb. 3, 2026

(54) **COMBINED REAGENT CONSUMABLE CAP AND TUBE**

(71) Applicant: **IDEXX Laboratories, Inc.**, Westbrook, ME (US)

(72) Inventors: **David Lance Connolly**, Eliot, ME (US); **Richard Andrews**, Gorham, ME (US)

(73) Assignee: **IDEXX LABORATORIES, INC.**, Westbrook, ME (US)

(**) Term: **15 Years**

(21) Appl. No.: **29/908,221**

(22) Filed: **Jan. 11, 2024**

(51) LOC (15) Cl. **24-02**

(52) U.S. Cl.

USPC **D24/224**

(57) **CLAIM**

The ornamental design for a combined reagent consumable cap and tube, as shown and described.

DESCRIPTION

FIG. 1 is a top perspective view illustrating a combined reagent consumable cap and tube;

FIG. 2 is a bottom perspective view of the combined reagent consumable cap and tube of FIG. 1;

FIG. 3 is a front elevation view of the combined reagent consumable cap and tube of FIG. 1;

FIG. 4 is a rear elevation view of the combined reagent consumable cap and tube of FIG. 1;

FIG. 5 is a right side elevation view of the combined reagent consumable cap and tube of FIG. 1;

FIG. 6 is a left side elevation view of the combined reagent consumable cap and tube of FIG. 1;

FIG. 7 is a top plan view of the combined reagent consumable cap and tube of FIG. 1; and,

FIG. 8 is a bottom plan view of the combined reagent consumable cap and tube of FIG. 1.
